UNITED STATES PATENT OFFICE.

BERTRAM NEUER WICKWIRE, OF CARBONDALE, PENNSYLVANIA.

SAFETY FASTENER.

1,404,818.

Specification of Letters Patent. Patented Jan. 31, 1922.

Application filed May 1, 1920. Serial No. 378,271.

To all whom it may concern:

Be it known that I, BERTRAM N. WICKWIRE, a citizen of the United States, residing at Carbondale, in the county of Lackawanna 5 and State of Pennsylvania, have invented a new and useful Safety Fastener, of which the following is a specification.

This invention aims to provide novel means for mounting a button on a door, 10 window or other closure, and to provide novel means for holding the button against movement.

Within the scope of what is claimed, a 15 mechanic may alter the precise structure depicted and described, without departing from the spirit of the invention.

In the drawings:—Figure 1 shows in elevation, a portion of a jamb and door to which the device hereinafter described has 20 been applied; Figure 2 is a section on the line 2—2 of Figure 1; Figure 3 is a section on the line 3—3 of Figure 1; Figure 4 is a view in perspective, showing the support which carries the button.

25 The numeral 1 marks a jamb and the numeral 2 designates a swinging closure, such as a door or window. The jamb 1 may carry a stop strip 3 against which the closure 2 abuts. The numeral 4 directs attention to a 30 support comprising an arm 5 and an arm 7 disposed at right angles to each other. The arm 7 has an opening 8 and there is an opening 6 in the arm 5. The arm 5 is provided with spaced chisel-shaped teeth 9 spaced 35 apart and disposed approximately parallel to the arm 7. A pivot element 10 is mounted in the opening 8 of the arm 7, a button 12 being mounted to swing on the pivot element in a plane parallel to the arm 7, one 40 end of the button projecting beyond the arm 5, a screw 15 being threaded into the other end of the button, the screw having a knob

14. The arm 5 extends along the edge of the jamb 1, a securing element 11 being inserted through the opening 6 into the jamb, 45 and the arm 7 extending along the side of the jamb. The construction above described comprises an unusually secure means for mounting the button 12 on the jamb for swinging movement. The screw 15 may be 50 advanced until it bears against the arm 7, the button 12 being held in overlapped relation with respect to the closure 2. The closure may carry a striking plate including flanges 16 and 18, united to the closure 2 by 55 securing elements 19 and 20, although, if desired, the flange 18 may be omitted.

I claim:—

In a device of the class described, a support comprising first and second arms disposed at right angles to each other, the second arm having a tooth extended in the same direction as the first arm and located approximately parallel thereto; a striking plate comprising a first flange alined with 60 the first arm of the support, and a second flange disposed parallel to the second arm of the support; a button pivoted to the first arm of the support and overlapping the first flange of the striking plate; a pivot 65 element connecting the button with the first arm of the support; and a screw threaded into the button and adapted to bear on the first arm of the support when the button overhangs the first flange of the striking 70 plate.

In testimony that I claim the foregoing as my own, I have hereto affixed my signature in the presence of two witnesses.

BERTRAM NEUER WICKWIRE.
